UNITED STATES PATENT OFFICE.

JOHN R. KELLER, OF GLENSHAW, PENNSYLVANIA, ASSIGNOR TO THE OHIO FOUNDRY
& MANUFACTURING CO., OF STEUBENVILLE, OHIO, A CORPORATION OF OHIO.

DESIGN FOR A GAS HEATER.

Application filed January 20, 1925. Serial No. 12,095. Term of patent 14 years.

To all whom it may concern:

Be it known that I, JOHN R. KELLER, a citizen of the United States, residing at Glenshaw, in the county of Allegheny, State of Pennsylvania, have invented a new, original, and ornamental Design for a Gas Heater, of which the following is a specification, reference being had to the accompanying drawing forming a part thereof.

The figure is a perspective view, looking from the front, of a gas heater showing my new design.

I claim:

The ornamental design for a gas heater, as shown.

JOHN R. KELLER.
